UNITED STATES PATENT OFFICE

136,302

DESIGN FOR A COFFEE MAKER

Harry Cunningham, New York, N. Y., assignor to Nathan Straus-Duparquet, Inc., New York,
N. Y., a corporation of New York

Application May 25, 1943, Serial No. 110,278

Term of patent 3½ years

To all whom it may concern:

Be it known that I, Harry Cunningham, a citizen of the United States, residing at New York, in the county of New York and State of New York, have invented a new, original, and ornamental Design for a Coffee Maker, of which the following is a specification, reference being had to the accompanying drawings, forming part thereof.

I claim:

The ornamental design for a coffee maker, substantially as shown.

HARRY CUNNINGHAM.
